UNITED STATES PATENT OFFICE

147,827

DESIGN FOR A COMBINED BRACELET AND WATCHCASE

Ernest Zimet, New York, N. Y.

Application December 30, 1946, Serial No. 135,853

Term of patent 7 years

(Cl. D45—4)

To all whom it may concern:

Be it known that I, Ernest Zimet, a citizen of the United States of America, residing in New York city, county of New York, and State of New York, have invented a new, original, and ornamental Design for a Combined Bracelet and Watchcase, of which the following is a specification, reference being had to the accompanying drawing, forming part thereof, wherein,

Figure 1 is a plan view of a combined bracelet and watchcase showing my new design.

Figure 2 is an edge elevational view of the combined bracelet and watchcase shown in Figure 1, showing the watchcase cover in open position.

I claim:

The ornamental design for a combined bracelet and watchcase, substantially as shown and described.

ERNEST ZIMET.
